VALVE

Arthur N. Asselin, Fall River, Mass.

Application June 15, 1936, Serial No. 85,408

5 Claims. (Cl. 137—68)

My invention relates to improvements in valves for humidifying apparatus for radiators, particularly steam and hot water radiators.

The primary object of my invention is to provide an efficient valve for humidifying apparatus for use in maintaining the proper degree of humidity and purifying the air in rooms heated by steam or hot water radiators and which is adapted for attachment together with said apparatus to standard types of such radiators and substantially concealed from view thereby.

Other objects are to provide a valve apparatus of the character and for the purpose above set forth for use in connection with evaporation tanks adapted to be set into the radiators in concealed positions and a fresh water supply for said tanks, and which is equipped with means controlled by the amount of water in said tanks to maintain said water at a fixed level and also controlled by an oversupply of water passing thereto to shut off said water supply.

Other objects are to provide a valve for the purposes above described which may be easily installed together with a humidifying apparatus on modern radiators, is absolutely reliable in operation, proof against flooding or leaking, requires a minimum amount of attention, and is comparatively inexpensive to manufacture.

Other and subordinate objects, together with the exact nature of my improvements, will be readily understood when the following description and claims are read with reference to the drawing accompanying and forming part of the specification.

In said drawing:

Figure 1 is a view in top plan, parts showing in section, of a control valve interposed in the line of connection between supply and evaporation tanks.

Figure 2 is a view in vertical longitudinal section of said valve.

My control valve 5 comprises an upstanding valve casing 15 forming a valve chamber 16 therein, a depending float casing 17 forming a float chamber 18 therein and an intermediate casing portion 19 between said casings connecting the bottom of the casing 15 to the top of the casing 17 to establish communication between said chambers 16 and 18. A pipe line 20 connects the top of the valve chamber 15 with one end of a supply tank (not shown) adjacent to the bottom of the latter. A branch line 20 connects the bottom of the float chamber 18 to evaporation tanks (not shown) at a point adjacent to the bottoms thereof and also connects said evaporation tanks with each other. A needle valve member 21 is slidably mounted in the valve chamber 16 for movement in opposite directions into engagement with oppositely disposed valve seats 22 and 23 to close said

chamber in either direction of its movement therein. The lower end of the valve member 21 extends into the intermediate casing portion 19 and is bifurcated, as at 24, for a purpose presently seen. A telescopic plunger rod 25 is slidably mounted in the top of the float chamber casing 17, centrally of the latter, in a sleeve 26 inserted through said top and into said chamber. The plunger rod 25 comprises upper and lower telescopic sections 27 and 28 having a slot 10 and pin connection 29 and 30, respectively, therebetween, for a purpose presently seen. The lower end of the section 28 is provided with a rubber tip 31 and the outer end of the upper section 27 with a hand-grip portion 32 and a lateral flange 33 below said portion. A coil spring 34 is interposed between the top of said casing 17 and a washer 35 resting on a pin 36 passing through the lower end of the section 28. A bifurcated bracket 37 is secured by rivets 38 in the intermediate casing portion 19 to the top wall thereof. A rocker arm 39 is pivotally mounted intermediate its ends, as by a pin 40, between the bifurcations of brackets 37 for vertical swinging movement. One end of the rocker arm 39 is operatively connected to the extending end of the valve member 21, between the bifurcations thereof, by a pin 41. The other end of the rocker arm 39 projects into the float chamber 18 and has suitably secured thereto a cylindrical float 42 closed at its bottom and depending into said chamber with the plunger rod 27 extending thereinto centrally thereof.

The plunger rod 27 is normally held elevated above the bottom of the float 42 and the spring 34 compressed by means of a trip latch 43 in the form of a hook pivotally mounted in the lugs 44 on the casing portion 19 to straddle said portion and for engagement of one end thereof with the under side of the flange 33. An overflow pan 45 is swingably and removably mounted between the arms of the latch 43 at the other end thereof and beneath the intermediate casing portion 19. A short sleeve 46 providing an overflow duct 47 is inserted upwardly in the bottom of said portion 19 to extend slightly above said bottom and above said pan.

The arrangement of the described parts is such that the float 42 normally counterbalances the valve member 21 into an intermediate opening position. In the described normal position of the parts, the water from the supply tank is free to flow through the valve 5 into the evaporation tanks, as will be understood. When the water has reached a proper level in the evaporation tanks, and in the float chamber 18, the float 42 rises and seats the valve member 21 against the lower valve seat 22, thereby cutting off the supply of water. Under these conditions the level of the water in the valve 5 is slightly be-

- low the top of the sleeve 46. In the event of leakage of an oversupply of water into the valve 5, for instance, in the case of improper engagement between the valve member and the seat 22, 5 the consequent overflow into said valve escapes through the port 47 into the pan 45 and upon sufficient accumulation therein swings the trip latch 43 out from under the flange 33, thereby unlatching and releasing the plunger rod 27. 10 Upon release of said rod the spring 34 thrusts said rod downwardly against the bottom of the float 42, thereby thrusting the latter downwardly and operating the valve member 21 in the opposite direction against the valve seat 23 to close 15 the valve 5 at this point.

- The beforementioned slot and pin connection 29 and 30 between the sections 27 and 28 of the plunger rod 25 is in the nature of a safety provision, preventing said rod from being thrust 20 downwardly beyond its valve-seating position. For this purpose the slot 29 and pin 30 are arranged so that in the valve-seating position of the rod 25 further downward pressure thereagainst is ineffective against the section 28. 25 The parts are re-conditioned for operation by pulling the plunger rod 25 outwardly, by way of the hand-grip 32, swinging the trip latch to its described position beneath the plunger 33 and suspending the pan 45, emptied of its contents, 30 on said trip latch.

- The foregoing constitutes a detailed description of a preferred embodiment of my invention and it is believed that its operation and construction will be clear therefrom. 35 Obviously, however, the details described may be varied without departing from the inventive concept disclosed, and it is to be understood that right is herein reserved to all such modifications falling fairly within the scope of the protection 40 prayed.

What I claim is:

1. A valve adapted to contain water at a fixed level and for the overflow of water therefrom beyond said level, a valve member in said valve 45 operative in opposite directions to different closing positions, respectively, operating means for said member including a float operative by rise of the water to said level to operate said member in one direction, a tensioned plunger for operating 50 said member in the opposite direction and movable to an ineffective position, and means for holding said plunger in said position and including a rocking trip yoke interlocking with said plunger, and a pan mounted on said yoke for receiving overflow water from said valve and tripping said yoke by the weight of water therein to disengage said yoke from said plunger. 55

2. A liquid level controlling valve comprising a housing having an outlet port, an inlet chamber 60 carried by said housing provided with spaced apart axially alined valve seats, a valve member in said chamber, a float in said housing, a rock lever carried by said housing having the ends thereof connected to said valve member and said 65 float respectively, spring-pressed means carried by said housing engageable with said float to lower said float in the liquid against the buoyancy of said float, said housing having an overflow port, a receptacle below said overflow port, and a rockable supporting member for said receptacle having an end thereof engageable with said spring-pressed means to normally hold said spring-

pressed means against operation, the weight of liquid in said receptacle swinging said supporting member to a position disengaged from said spring-pressed means.

3. A liquid lever controlling valve comprising 5 a housing having a lower outlet port and an overflow port above said outlet port, an inlet chamber carried by said housing provided with spaced apart axially alined valve seats, a valve member in said chamber, a float in said housing, a rock lever carried by said housing having the ends thereof connected to said valve member and said float respectively, a spring-pressed plunger slidably carried by said housing engageable with said float to lower said float in the liquid against the 15 buoyancy of said float, said housing having an opening through which said plunger engages, a receptacle disposed below said overflow port, and a rockable supporting member for said receptacle having an end thereof engageable with said 20 plunger to normally hold said plunger against operation, the weight of liquid in said receptacle swinging said supporting member to a position disengaged from said plunger.

4. A liquid lever controlling valve comprising 25 a housing having a lower outlet port and an overflow port above said outlet port, an inlet chamber carried by said housing provided with spaced apart axially alined valve seats, a valve member slidable in said chamber, a float in said 30 housing, a rock lever carried by said housing having the ends thereof connected to said valve member and said float respectively, spring-pressed means carried by said housing engageable with said float to lower said float in the liquid against 35 the buoyancy of said float, a receptacle communicating with said overflow port, and a combined trigger and receptacle supporting member rockably carried by said housing, said supporting member having an end thereof engageable with 40 said spring-pressed means to normally hold said spring-pressed means against operation, the weight of liquid in said receptacle swinging said supporting member to a position disengaged from 45 said spring-pressed means.

5. A liquid lever controlling valve comprising a housing having a lower outlet port and an overflow port above said outlet port, an inlet chamber carried by said housing provided with spaced apart axially alined valve seats, a valve member in said chamber, a float in said housing, a rock lever carried by said housing having the ends thereof connected to said valve member and said float respectively, a spring-pressed plunger in said housing engageable with said float to lower said float in the liquid against the buoyancy of said float, a flanged sleeve slidably carried by said housing engaging about a portion of said plunger, said sleeve having opposed elongated slots, a pin carried by said plunger loosely 60 engaging in said slots, a receptacle disposed below said overflow port, and a rock member carried by said housing having one end thereof detachably secured to said receptacle and the other end thereof engageable with the flange of 65 said sleeve to thereby hold said plunger in inoperative position, the weight of liquid in said receptacle swinging said rock member out of engagement with said flange to thereby release said plunger for engagement with said float. 70
